US0D1068383S

(12) **United States Design Patent** (10) **Patent No.:** **US D1,068,383 S**
Hong (45) **Date of Patent:** **** Apr. 1, 2025**

(54) **VACUUM INSULATED MUG**

(71) Applicant: **SHENZHEN HUIHUI TECHNOLOGY CO., LTD**, Shenzhen (CN)

(72) Inventor: **Xianhe Hong**, Shenzhen (CN)

(73) Assignee: **SHENZHEN HUIHUI TECHNOLOGY CO., LTD**, Shenzhen (CN)

(**) Term: **15 Years**

(21) Appl. No.: **29/872,383**

(22) Filed: **Mar. 12, 2023**

(51) **LOC (15) Cl.** **07-01**

(52) **U.S. Cl.** **USPC** **D7/511**

(58) **Field of Classification Search**

(57) **CLAIM**

The ornamental design for a vacuum insulated mug as shown and described.

DESCRIPTION

FIG. 1 is a perspective view of a vacuum insulated mug showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 8 Drawing Sheets
